ASSEMBLING JIG

Original Filed Dec. 6, 1930

UNITED STATES PATENT OFFICE

JAMES C. DAWSON, OF WEBSTER GROVES, MISSOURI, ASSIGNOR TO ELMA N. DAWSON,
OF WEBSTER GROVES, MISSOURI

ASSEMBLING JIG

Original application filed December 6, 1930, Serial No. 500,449. Patent No. 1,842,249, January 19, 1932.
Divided and this application filed December 21, 1931. Serial No. 582,313.

The invention relates to jigs especially adapted for the assembling of a certain type of loose leaf binder mechanism, and this application is a division of my pending application Serial No. 500,449, filed December 6, 1930 and patented January 19, 1932, Number 1,842,249, on Method and apparatus for manufacturing loose leaf binders.

The objects and preferred form of construction of the invention will be best set out in the following description.

In the drawing:

Figs. 1, 2 and 7 illustrate forms of binder mechanism in connection with the manufacture of which the improved jig is employed;

Fig. 3 is a detail plan view of the jig;

Figs. 4 and 5 are sectional views, respectively, on the lines 4-4 and 5-5 of Fig. 3; and

Fig. 6 is a view similar to Fig. 5, slightly modified.

In the form of binder mechanism in connection with the manufacture of which the improved jig is employed, there is present a spring plate 11, having its margins in-turned, as shown at 37 (Fig. 6), a pair of arch wires 12, 13, being held within the downturned margins and having their end portions brought into engagement to form toggle joints and then bent to form a half of a binding ring, as shown at 16, 17, these ring sections extending through apertures 18 in the plate. Intermediate of the end rings is a third sectional ring 14, the inner ends of the two sections being pivotally united, as plainly shown in Figs. 2, 5, 6 and 7. Each of these ring sections 14 is permanently attached to one of the wires 12, 13, and extends through apertures 15 in the plate 11 which correspond to the apertures 18.

The manufacturing problem which is solved by means of the improved jig was in the assembling of the parts of the binder, the proper positioning of the sections of the ring 14 preliminary to their attachment to the wires 12, 13, in order that the three rings should close simultaneously.

The jig consists of a metal block 19, having transverse apertures in its upper face spaced to receive the ring elements 16, 17,

when the latter are assembled with the plate 11. These apertures are contracted toward their bottoms, the upper portions 29 of their end walls being preferably straight and their lower portions being of arcuate form, as shown at 21, 22. Crossing the bottoms of each of these apertures is a thin spacing plate 26.

If desired the described apertures may be formed in blocks, as 40, fitting within recesses in the block 19. Midway between the described apertures the block 19 is apertured in its upper face, as indicated at 41; the walls of this aperture extending lengthwise of the block being provided with instanding shoulders 25, forming tracks upon which a pair of blocks 23, 24, are slidably mounted. The adjacent faces of the last-named blocks are recessed to receive between them the ring sections 14, these recesses being provided with straight walls 29, and arcuate walls 28 corresponding with the walls 21, 22, each recess being crossed at its bottom by a short guide plate 27.

The several elements of the binder being roughly assembled, the rings 14, 16 and 17, however, being open, the binder is inverted and applied to the jig, the prongs of the several rings being forced into its apertures and thereby closed together but for the spacing due to contact with the plates 26, 27. Thus the central ring 14 is accurately positioned with reference to the end rings. The blocks 23, 24, are now closed firmly together and all of the parts are thereby rigidly held, while the two sections of the intermediate ring 14 are secured to the wires 12, 13, by any suitable means.

In the embodiment of the invention disclosed electric welding is employed for fastening these parts together. The blocks 23, 24, constitute one electrode, and a two-point electrode 31 is applied to the two arch wires 12, 13, as shown at 33, 34, and upon the passage of current the welding action takes place between the ring sections and the wires 12, 13, at the points 35, 36. The electrode 31 is arched, as shown at 32, to prevent contact directly with the ring elements.

The attachment having been accomplished, the binder mechanism is withdrawn from the jig, whereupon, by reason of the spring action of the plate 11, the sections of the several rings are closed together.

5 The improved jig is capable of use in connection with other forms of the type of binder illustrated, as, for example, the form constituting the subject-matter of my pending application Serial No. 519,945, filed 10 March 4, 1931, for improvements in loose leaf binders.

I claim as my invention—

1. In an assembling jig for loose leaf binders, a metal body having transverse slots of arcuate form for receiving the elements of the binder rings and forcing them together, and spacing plates at the bottoms of the slots for engagement by the ends of 15 such elements.

2. In an assembling jig for loose leaf binders comprising a pair of arch wires having integral sheet-holding prongs and an intermediate pair of cooperating prongs attached to the wires, a metal body having transverse arcuate slots for receiving the first-named prongs and an intermediate aperture, a pair of clamping blocks mounted within the aperture and having mating arcuate grooves in their adjacent faces which together form a groove for receiving the intermediate prongs, and spacing plates crossing the slots and groove.

3. In an assembling jig for loose leaf binders comprising a spring plate, wires pivotally held by the marginal portions of the plate, and a plurality of jointed openable holding rings carried by the wires, a metal body having transverse arcuate slots for receiving the free ends of the ring elements, and spacing abutments at the bottoms of the 35 slots.

In testimony whereof I affix my signature.

45

JAMES C. DAWSON.
